Application May 13, 1942, Serial No. 442,821

1 Claim. (Cl. 153—51)

The present invention relates to new and useful improvements in presses adapted for reshaping warped surfaces of metal plates, such as used in ship building and similar purposes, and the invention has for its primary object to provide upper and lower clamping plates between which the work is positioned, said clamping plates being formed of segments and providing means for the individual adjustment of each segment to provide an adjustable form within which the work is positioned for reshaping the same in a desired manner.

A further object is to provide an apparatus of this character of simple and practical construction, which is efficient and reliable in performance, strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a vertical longitudinal sectional view.

Figure 2 is a vertical transverse sectional view.

Figure 3 is a horizontal sectional view taken substantially on a line 3—3 of Figure 1.

Figure 4 is a horizontal sectional view through one of the guide channels and rollers.

Figure 5 is a fragmentary sectional view through one of the adjustable ball and socket segments for the form, and

Figure 6 is a fragmentary side elevational view of the guide shoe for the base of the lower adjustable form.

Referring now to the drawings in detail, wherein for the purpose of illustration I have disclosed a preferred embodiment of the invention, the numeral 5 designates a plurality of spaced posts having their lower ends suitably anchored in the ground or other permanent structure, the posts being of channel shape in cross-section with the channel of each pair of posts disposed in opposed relation, as shown to advantage in Figure 3 of the drawings.

The upper ends of the posts are connected by beams 6, likewise of channel shape in cross-section.

An upper form is designated generally at 7 and includes a horizontal plate 8 supported beneath the beams 6 by vertically disposed spaced parallel webs 9, the webs 9 preferably being welded or otherwise suitably connected to the beams and

the plate; the webs 9 having aligned openings 10 formed therein.

Screws 11 are threaded through the plate 8 and freely through a plate 12, disposed in spaced relation beneath the plate 8, the plate 12 being adjustable vertically with respect to the plate 8 and secured in adjusted position by means of nuts 13. The screws 11 are also adjustably secured in the plate 8 by means of nuts 14.

The edges of the plate 12 are provided with upper and lower rollers 15 and 16 journaled in brackets 17 and 18 secured to the plate, the rollers travelling along the edges of the channel-shaped posts 5.

Balls 19 are formed on the lower ends of the screws 11, swivelly secured in sockets 20 by set screws 21, the sockets 20 being formed on the upper surface of foot members 22, the foot members having substantially square surfaces, as shown to advantage in Figure 3 of the drawings, and with their edges disposed in close relation with respect to each other and cooperating to form an upper segmental plate for the form 7.

A flexible lining 23 is secured to the lower surfaces of the foot members 22 by means of screws 24 and positioned between the lining 23 and the foot members 22 is a lining of insulation material 25, which may be of asbestos or the like.

A lower form is designated generally at 26 which includes a head plate 27 secured on the upper end of a hydraulically operated ram 28 by means of beams 29, the plate 27 having a plurality of horizontally spaced upstanding webs 30 secured thereto for supporting a plate 31 on the upper edges of the webs, the webs preferably being secured to the plate of welding or the like.

Screws 32 are threaded upwardly through the plate 31 and freely through a top plate 33, the screws being secured in adjusted position by means of the nuts 34 and 35.

The screws 32 are constructed similarly to the screws 11 to provide the lower segmental clamping plates 36 on the upper ends of the screws 32 for cooperating with the upper segmental clamping plates as heretofore explained.

The plates 31 and 33 are provided at their edges with the guide rollers 37 and 38 similar to the guide rollers for the plate 12 and are adapted likewise to travel along the edges of the posts 5.

Rollers 39 are journaled in the posts 5 by means of pins 40 and bearings 41 and engaged with the rollers 39 are shoes 42 secured on the vertical sides of the head member 27.

In operation of the device, it will be apparent that the segmental upper and lower clamping

plates may be adjusted by the screws 11 and 32 into a desired shape and by placing the preheated steel plates between the clamping plates and actuating the hydraulic plunger 28 upwardly, the plate will be clamped between the clamping plates to reshape the same in a manner as will be apparent.

It is believed the details of construction, operation and advantages of the device will be readily understood from the foregoing without further detailed explanation.

Having thus described the invention what I claim is:

A press of the class described comprising a plurality of posts, rollers journaled in said posts, an upper clamping member including a stationary plate, a movable rigid plate and segmental clamping plate, screws connecting the plates to provide vertical adjustment of the movable plate relative to the stationary plate and for independent vertical adjustment of the segments of the

clamping plate relative to both the stationary plate and movable plates, rollers carried above and below the movable plate adapted to travel along the edges of the posts, a lower clamping member including a base, a plate fixed to the base, a movable rigid plate, and a segmental clamping plate, screws adjustably connecting the last-named segmental clamping plate to the last-named movable rigid plate and also connecting the last-named movable rigid plate to the last-named fixed plate, rollers carried above and below both the last-named movable plate and to the plate fixed to the base and adapted to travel along the edges of the posts, shoes carried by the base and adapted to travel over said first-named rollers, and means connected to the base for moving the lower clamping member in a manner to compress work against the upper clamping member.

TOM WALTERS.
